AUTOMOBILE WHEEL COVER

Donald F. Kopka, Berkley, Mich., assignor to Chrysler Corporation, Highland Park, Mich., a corporation of Delaware

Application June 11, 1956, Serial No. 41,839

Term of patent 7 years

(Cl. D14—30)

Fig. 1 is a front elevational view of an automobile wheel cover showing my new design; and

Figs. 2 and 3 are sectional views taken on the lines 2—2 and 3—3, respectively, of Fig. 1.

The dominant features of my design reside in the portions shown by means of full lines in the drawing.

I claim:

The ornamental design for an automobile wheel cover, substantially as shown and described.
